UNITED STATES PATENT OFFICE

2,419,432

ELECTRIC PROJECTOR LAMP

Daniel K. Wright, Cleveland Heights, Ohio, assignor to General Electric Company, a corporation of New York

Application December 1, 1944, Serial No. 566,193

1 Claim. (Cl. 176—34)

1

This invention relates to electric lamps of a general type such as disclosed in my Patents Nos. 2,148,314 and 2,148,315, granted February 21, 1939, and 2,324,972, granted July 20, 1943, which are commonly known as the "Sealed Beam" type, and are widely used as automobile headlamps. This type of lamp comprises a bulb or envelope composed of sections hermetically sealed together at their edges, one a rear section which generally serves as a reflector, and the other a front cover or lens section. As shown in said patents, the sections are of vitreous material pressed or molded to shape and afterward united at the edges by fusion, and the sections are concave toward one another. The rear section may have a concave light-concentrating surface, preferably paraboloidal when a straight, uniform light beam is desired, with the electric translation means or light source located or centered at its focus. The front cover section may be plain, depolished or matte, frosted, pebbled, fluted, or prisms to transmit and distribute the light or radiation as desired. The initial separateness of the sections facilitates shaping their internal surfaces by pressing exactly as desired, and also facilitates internally coating the rear section (only) with a metallic mirror of silver, aluminum, or other suitable metal(s). These parts may be of low-expansion glass such as the borosilicate glass disclosed in U. S. Patent No. 1,304,623 to Sullivan et al.

It has heretofore been sought to provide lamps such as above described with light-polarizing front cover glasses. This is especially desirable for automobile headlight lamps, as a means of abolishing the danger and annoyance of blinding glare from the undimmed bright lights of an approaching car at night; i. e., a driver with polarized headlights and similarly polarized glasses would see the road brightly lighted ahead of him by his own lights, but would get neither direct nor road-reflected glare from the polarized headlights of a car coming in the opposite direction. But it has been found difficult and expensive to apply light-polarizing material to the externally convex or crowned covers of such headlamps; and it has proved impracticable to make flat-front lamps (i. e., lamps with flat front sections) to which commercially available sheet or laminated polarizing material could readily be applied, because the envelopes of lamps made with such flat fronts have tended to crack after their component sections have been sealed together, resulting in prohibitively high losses in production.

2

I have found that by certain modifications of structure and of sealing technique which I have devised, flat-front Sealed Beam type lamps can be produced without serious risk that their composite envelopes will crack as heretofore, and light-polarizing lamps of this character can likewise be produced very easily and economically. The invention also allows of making flat-front Sealed Beam type lamps that are useful in cases where light polarization is unnecessary. Two specific ways of sealing flat front cover sections to rear sections for the purposes of the invention are hereinafter described, and have in common the novel feature that the sealing heat is largely kept away from the flat part of the cover.

Various other features and advantages of the invention will appear from the description of species and forms of embodiment, and from the drawings.

20 In the drawings, Fig. 1 is a plan view of a flat-front light-polarizing lamp constructed according to the invention, the lamp envelope being shown partly broken away and in section at several places, and its component sections being represented as sealed together only part way around their peripheries; and Figs. 2 and 3 are front and rear views of the component rear and front glass sections by themselves, prior to sealing together, part of the front section being broken away and omitted from Fig. 3.

30 Figs. 4 and 5 are fragmentary views generally similar to Fig. 1 illustrating other ways of applying a light-polarizer to a flat-front lamp.

Figs. 6 and 7 are tilted front and rear views 35 of rear and front lamp sections, illustrating a modification; and Fig. 8 is a fragmentary sectional view illustrating the forming of a joint between these sections when they are fused and sealed together.

40 A sealed beam lamp bulb or envelope 1 is shown in Figs. 1, 2, and 3 as comprising a rear pre-formed pressed glass concave reflector section 2 internally surfaced with a reflective metallic coating 3, and resembling the reflector section 45 shown in my Patent No. 2,324,972. It has a widened periphery or rim 4 that has a sealing zone 5 for sealing to the front section 6, also preformed of pressed glass: This front lens or cover section 6 differs from that of said patent 50 in being dish-shaped and having a radiation-transmitting portion that is substantially flat or planar instead of concave, with a lateral flange or circumferential wall 7 extending to the reflector rim 4 for sealing thereto, and peripherally 55 widened into a rim 8 that affords a sealing zone

9 corresponding to the sealing zone 5. Both these sections 2, 6 are preferably of low-expansion heat-resistant glass. Within the envelope 1, at or in definite optical relation to the focal point of the reflecting surface 3, is mounted the electrical energy-translation means or light source 10, here represented merely by a single linear coil of refractory metal such as tungsten. As shown in Fig. 3, the inner surface of the cover or lens 6 has flutings 11 for directing and distributing the light from the translation means 10 as desired. The inlead connections 12, 12 through the reflector 2 and their vacuum and gas-tight seals may correspond to what is shown in my last-mentioned patent, and the connections 12, 12 are shown as provided with apertured external bracket terminals 13, 13 behind the reflector 2. After the sections 2 and 6 have been sealed together, the envelope 1 may be evacuated and filled with a suitable gaseous medium (if desired) by means of an exhaust tube 14 at the apex of the reflector 2, after which this tube may be tipped or sealed off as shown.

As shown in Figs. 2 and 3, the rims 4 and 8 and the sealing zones 5 and 9 of the sections 2 and 6 may correspond essentially to those in my last-mentioned patent: e. g., the annular sealing zones 5 and 9 may have a uniform mating width of about $\frac{1}{8}$ inches. Inside the zone 5, likewise, the rim 4 may be rabbetted on a bevel to a depth of some $\frac{1}{2}$ inch and a bottom width of about the same, and inside the zone 9, the rim 8 may be rabbetted to a similar bottom width, though to a much less depth. To align the section 6 coaxially with the section 2 for sealing thereto, these parts are provided with interlocking matched protuberances or keys 15 and depressions or keyways 16. Preferably the keys 15 are of slightly greater height or depth than are their corresponding keyways 16. As indicated in Figs. 1, 2, and 3, there are four keys 15 on the front section 6 and four corresponding keyways 16 in the rear section 2, all spaced 90°. To orient the lens features 11 of the cover 6 relative to the reflector 2 and the translation means 10, one projection 15 and its corresponding recess or socket 16 are made larger than the others. As shown, the keys and keyways 15, 16 occupy about half the width of the zones 9, 5 at their outer edges. In practice, the keys 15 may be about $\frac{1}{8}$ inch wide and $\frac{1}{2}$ inch high, with a length of about $\frac{1}{4}$ inch circumferentially of the zone 9 for all but one of them, which may be about double this length.

In sealing the sections 2 and 6 together, the reflector section 2 is mounted face-up in a rotatable holder (not shown), and the cover section 6 rests thereon by its own weight, being properly aligned and oriented (with the sealing zones 5, 9 in registry) by the interfitting and interlocked key means 15, 16. The assembled sections 2, 6 are then rotated while sharp-pointed sealing flames 17 (only one of which is indicated in Fig. 1) play on the "joint" of the sealing surfaces 5, 9, until the glass at these surfaces becomes fused and unites the parts in a fused glass seal. While this seal is still soft and plastic, air or gas under pressure may be admitted to the envelope 1 through the exhaust tube 14 to "blow up" or raise the cover 6 slightly (the extent may be determined by suitable stop means, not shown), thus stretching or working the glass of the seal and producing a rounded inner seal boundary 18, Fig. 1, which makes for a strong, strain-free joint—as contrasted with a sharp crevice or

corner in the seal, which would make for weakness and easy initial cracking through the joint.

During the formation of the joint as just described, heat therefrom travels inward in the cover rim 8 and into the circumferential wall or flange 7, tending to soften it or at least reduce its resistance to stress, so that it does not become strained or internally stressed. At the same time, the wall 7 serves to isolate the flat radiation-transmitting cover portion from the rim 8, so that no dangerous thermal strain or internal stress is set up in this flat portion. Accordingly, the envelope 1 formed by the interfusion of the sections 2, 6 is free from strain or stress that would tend to produce cracking. This is in marked contrast with the reverse situation in the case of a mere flat cover with its margin lapped over the reflector sealing zone 5 and fused directly thereto.

20 A polarizing layer 19 may be applied to the flat front face of the cover 6 very easily and conveniently, preferably after the cover 6 has been sealed to the rear section 2. For this purpose, I may use a commercially available polarizing sheet material consisting of a transparent carrier sheet of plastic having thereon an adherent film of oriented polarizing particles, and preferably provided with a coating of thermo-softening adhesive over its polarized face. The cover 6 being gently heated or warmed, a suitable sheet of this character is laid on its front face with the adhesive next the glass, and is pressed against the glass until firmly bonded thereto all over, as shown in Fig. 1.

face of the cover rim 8 sufficiently to unite and seal the parts together; but this is preferably accomplished without melting down the flange 5, which as shown in Fig. 8 retains almost its full height. The cover rim 8 is not appreciably modified by the sealing operation, except in being stuck to the top of the flange 5 to form a gas and vacuum-tight seal of ample mechanical strength. No light-polarizer is shown in Figs. 6, 7, 8, although one might obviously be applied in the same way as in Fig. 1.

The modification here described in connection with Figs. 6, 7, and 8 has been found especially suitable for relatively small lamps, of some 4 or 5 inches diameter. For ordinary head-lamps of 15 some 7 inches diameter or larger, the construction described in connection with Figs. 1, 2, and 3 may be preferred as giving greater strength.

It will be understood that the dimensions and materials hereinbefore mentioned are illustrative, and are not to be taken as defining or limiting the invention, since in practice the dimensions may be varied and other materials may be used.

In Figs. 4, 5, 6, 7, and 8, various parts and features are marked with the same reference characters as their homologues in Figs. 1, 2, and 3, as a means of dispensing with repetitive description.

What I claim as new and desire to secure by Letters Patent of the United States is:

A projection lamp comprising a glass reflector section and a dish-shaped glass cover section with a planar end wall portion and a circumferential side wall portion fused at its periphery to the periphery of said reflector section and forming an enclosure for a light source, said cover section having a forwardly projecting marginal flange, and a secondary planar cover section carrying a film of light-polarizing material and secured to the said marginal flange in spaced relation to the surface of the end wall portion of said first-mentioned cover section.

DANIEL K. WRIGHT.
